Louis L. Randall Inventor

UNITED STATES PATENT OFFICE.

LEWIS L. RANDALL, OF OTTUMWA, IOWA.

CHURN.

1,190,191.

Specification of Letters Patent.

Patented July 4, 1916.

Application filed August 18, 1911. Serial No. 644,895.

To all whom it may concern:

Be it known that I, LEWIS L. RANDALL, a citizen of the United States, residing at Ottumwa, in the county of Wapello and State of Iowa, have invented certain new and useful Improvements in Churns; and I do hereby declare the following to be a full, clear, and exact description of the invention, such as will enable others skilled in the art to 10 which it appertains to make and use the same.

This invention is a churn having for its object to provide an economical device capable of operating upon a large amount of 15 cream for the purpose of producing butter.

Another object of the invention is to provide a receptacle of peculiar shape wherein the liquid may be conducted from end to end of the receptacle thereby giving greater 20 distance to the movement of the liquid within the churn.

The churn comprises a receptacle, preferably of wood, having a plurality of semi-cylindrical end sections and a central section, 25 and a removable cover at the top of the receptacle for the purpose of attaining access to the interior thereof. The receptacle is mounted upon a suitable framework and is provided with means for imparting rotary 30 motion to said receptacle.

In the accompanying drawings, I have illustrated a preferred embodiment of the invention wherein like reference characters denote similar parts in all the figures.

Figure 1 is a side elevation of the churn mounted upon a support. Fig. 2 is a vertical sectional view through the receptacle member. Fig. 3 is a front elevation of the dasher. Fig. 4 is a plan view of the churn and support. Fig. 5 is a detail view of the plate having a stub shaft for the receptacle. Fig. 6 discloses staves separated by a metallic strip.

The receptacle for cream, and the like, 45 consists of two semi-cylindrical end sections A, B, and a central section C, which latter section is provided with substantially straight walls. The receptacle is preferably constructed of wood, and I have found 50 it desirable to make it of cedar or white oak wood.

The sections A, B are substantially equal in contour to an ordinary barrel or keg which has been split longitudinally into approximately equal halves. The staves a, b,

comprising these sections A, B, are of greatest width at or near the central portion of their length, and are provided with beveled edges, when necessary, to produce the proper curvature or contour to the receptacle, as is the usual construction of barrels or kegs (see Fig. 4). The staves c of the central section C, however, are substantially the same width throughout their length, and the edges of these staves are substantially at 60 right angles to the face thereof and not beveled as is the case with the staves a, b. These staves a, b, c, when constructed of certain woods, such as cedar, may be separated by a metal strip b'', such as aluminium for the purpose of maintaining the receptacle water tight, see Fig. 6. All of the staves are bound together to retain the receptacle in operative form by any suitable means such as the hoops y. It may be necessary to construct staves a', b', which separate the central section C from the end sections a, b, of a little different shape from the other staves comprising the receptacle, as is shown in Fig. 2. 65

Access to the interior of the receptacle is attained through an opening x in the end thereof, the edges being provided with suitable means for producing a water tight joint with a removable cover member D. 70 This cover member is shown in Figs. 2 and 4. The cover D is retained in position by leaf springs E (Fig. 4), which are pivoted centrally, at e, for the purpose of permitting the free ends of the spring to engage suitable means (not shown) in the ends of the receptacle, for the purpose of retaining the springs under tension. 75

The receptacle is mounted upon a suitable frame comprising base members F, connected with upright converging members F', said members F' meeting at F² to support a journal bearing for the receptacle. 80

The receptacle is provided with a plate G, (Figs. 1 and 5) upon each side thereof, said plate being secured to the central section C. Each of these plates G is provided with a suitable stub-shaft adapted to rotate in the journal bearing F², while on one of said stub shafts there is positioned a crank arm H for 85 the purpose of revolving the receptacle upon its frame.

Interiorly of the receptacle there is positioned a plurality of dashers J, K, (Figs. 2 and 3) which are united at substantially 90

the central portion thereof by a rod L. The dashers K are retained in fixed relation to the end walls of the churn, when it is in operation, by any suitable means, such as the 5 tongues k engaging grooves or slots in the bottom of the receptacle, and its removable top member, respectively. The dashers J are pivotally mounted upon the rod L, and when cream is placed within the receptacle 10 these dashers occupy substantially the position shown in Fig. 2. These dashers J are capable of considerable movement but are prevented from completely revolving within the receptacle by the cross stave M, which is 15 united to the fixed dashers K. The dashers J, K, are removably positioned within the receptacle, as will be understood.

In the preferred form of the device, the opening α is provided with a flanged casting P fitting the sides of the opening. This casting is retained in position by having means which fit into the croze on either side of the central section C. This croze is similar to the ordinary croze of a barrel with 20 the exception that in the present device it is straight to correspond to the central section, instead of curved. To make the cover member D water tight, I employ a tubular rubber packing which is retained in position on 25 the flange of the casting, to conform to the shape thereof, by any suitable non-rusting or non-corrosive metal, such as an aluminum wire. When the cover D is clamped in position by the springs E, engaging their 30 bearing members on the sides of the receptacle, the edges of the cover D will be forced into engagement with the flanged casting and compress the tubular packing, thereby 35 forming a water tight joint.

40 In operation, the desired quantity of cream is placed within the receptacle, the dashers J and K brought into substantial alignment with each other and passed through the opening α into the receptacle 45 until the tongues k engage the slots in one end thereof, whereupon dashers J are free to assume their horizontal position. The cover member D is now placed in position to close the opening α , and the springs E turned 50 upon their pivot e for the purpose of locking the cover in position. The receptacle may now be revolved upon its frame by turning the crank H causing the cream to 55 pass into contact with, and between, the fixed and movable dashers, J, K, respectively, as the liquid rushes from end to end of the receptacle. When butter has been produced, the parts are removable, as will be readily understood by those skilled in the art.

60 Having thus fully described my inven-

tion what I desire to claim as new and secure by Letters Patent is:—

1. In a churn, a frame, a receptacle comprising two semi-cylindrical end members and a substantially straight central member, a removable cover positioned at one end of said receptacle and means for completely revolving said receptacle end for end with reference to said frame. 65

2. In a churn, a frame, a substantially elliptical receptacle mounted for rotative movement thereon, a plurality of dashers retained in fixed relation to said receptacle, a plurality of other dashers, capable of movement with reference to said receptacle, and 75 means for revolving said receptacle on said frame. 70

3. In a churn, a frame, a receptacle comprising two semi-cylindrical end members having tapering staves, a central member 80 having substantially straight rectangular staves, means for retaining said staves in an operative position, a removable dasher mounted in the central member, a removable cover mounted between the semi-cylindrical end members, and means for revolving said receptacle end for end upon the frame. 85

4. In a churn, a frame, a receptacle comprising two cylindrical end members having tapering staves, a central member having 90 substantially straight rectangular staves, metallic strips positioned between said staves, means for retaining the staves in an operative position, a removable dasher mounted within the central member, a removable cover for said central member, said cover having resilient retaining means adapted to engage the central member, and means for revolving the receptacle end for 95 end upon said frame. 100

5. In a churn, a frame, a substantially elliptical receptacle having a straight central member, a removable cover for said central member, a removable dasher mounted within said central member, said dasher comprising a series of fixed members and a series of movable members, said fixed and movable members being connected by a central rod, a stay for connecting said fixed dashers and for limiting the movement of the movable dashers, and means for revolving said receptacle end for end upon the frame. 105 110

In testimony whereof, I affix my signature in the presence of two witnesses.

LEWIS L. RANDALL.
